UNITED STATES PATENT OFFICE.

JOSEF VOSKA AND CHARLES NELSON, OF BROOKLYN, NEW YORK, ASSIGNEES TO S. STERNAU & COMPANY, OF NEW YORK, N. Y., A COPARTNERSHIP.

ASH-RECEIVER.

No. 902,511.

Specification of Letters Patent.

Patented Oct. 27, 1908.

Application filed February 6, 1908. Serial No. 414,661.

To all whom it may concern:

Be it known that we, JOSEF VOSKA, a subject of the Emperor of Austria, and a resident of the borough of Brooklyn, county of Kings, and State of New York, and CHARLES NELSON, a subject of the King of Sweden, and a resident of the borough of Brooklyn, county of Kings, and State of New York, have invented a new and useful Ash-Receiver, of which the following is a specification.

The object we have in view is the production of an ash receiver, which may be used with or without a stand, so arranged that the receiver may be locked to the stand so that it will not become accidentally displaced therefrom.

Further objects are to produce an ash receiver which may be used alone, which may be made of pleasing proportions, and which will effectively prevent hot ashes or burning cigars deposited in the receiver from injuring the table or other furniture or furnishings upon which it is carried.

These and further objects will appear from the following specification and accompanying drawings, considered together or separately.

We attain these objects by the devices illustrated in the accompanying drawings, in which

Figure 1 is a side elevation of the ash receiver and stand embodying our invention. Fig. 2 is a plan view of the ash receiver and a portion of the stand. Fig. 3 is a sectional view of the same. Fig. 4 is a view of a portion of the stand and a portion of the receiver showing the stand disengaged from the receiver.

In all of the views like parts are designated by the same reference characters.

In carrying out our invention we provide an ash receiver 1 and a stand 2, the ash receiver being adapted to rest upon the stand and being adapted to be removably connected thereto. The ash receiver comprises an outer casing 3 and an inner casing 4. The inner casing 4 is open at the top and closed at the sides and bottom, and is provided at its edge with a beading 5, which rests upon and covers the unbeaded edge of the outer casing 3. This provides a support for the inner casing, keeping the bottom of such inner casing clear of and away from

the bottom of the outer casing. It also provides a finish for the edge of both casings. The beading 5 is completely turned over so that there is sufficient space left for the upper edge of the outer casing to enter the turned-over portion, as is shown in Fig. 3. The outer casing is deeper than the inner casing and flares outward toward the bottom, producing a curved flange or offset 6. The beading 5 of the inner casing carries the cigar supports 7—7 and a match-box holder 8. The number and arrangement of the cigar supports and match-box holders may be varied, as is obvious. The ash receiver may be used alone, upon a table, desk or other support, or may be used in connection with the stand 2.

The stand, as shown, comprises legs 9; in the embodiment illustrated, there being three. These legs are made of rods, preferably of elastic material, and flare out at the bottom, and are connected together by the rings 10 and 11, the ring 11 being much smaller than the ring 10. Above the ring 11 the legs gradually converge together to the point 12, and then diverge so as to form a support which grasps the receiver and engages with the outer casing 4 thereof. The upper ends of the legs are provided with bosses or enlargements 13, which are adapted to engage with the curved flange 6, already described. These legs and bosses are pressed into engagement with the flange 6, by means of a movable ring 14. This ring surrounds the legs below the converging point 12 at a place where the legs 9 are further apart. By raising up the ring 14 the legs may be separated so that the ash receiver may be lifted out of engagement with the legs.

We prefer to give the legs a permanent diverging set and make them of an elastic material, preferably spring brass, so that when the ring 14 is raised the upper ends of the legs will spring apart, as shown in Fig. 4. To prevent the ring accidentally rising, one of the legs is provided with a notch 15, located at the upper point so as to engage with the ring 14 and prevent it from rising. The ring is shown in Fig. 3 as in engagement with the notch, and in Fig. 4 as lifted above the notch. The rings 10 and 11 may be permanently secured to the legs by any means, such as by means of the

screws, as illustrated. The lower ends of the legs may be provided with bosses or other ornamental feet, as shown.

By our invention an ash receiver is produced which is of a highly ornamental nature. The ash receiver is firmly locked to the stand, but it may be readily removed in the manner already described. The ash receiver may be emptied of ashes and cleaned by simply lifting out the inner casing 4. By making the inner casing 4 of less depth than the outer casing 3, the latter may be made of a depth sufficient to secure the proper portions to insure a pleasing appearance, which depth is greater than the depth of the inner casing could advantageously be. Another advantage is that the outer and inner casings may be made of materials of contrasting color and appearance; as an example, the inner casing 20 may be made of brass and the outer casing 25 may be made of copper, producing a very pleasing appearance. Another advantage in having the inner and outer casings of less depth is that an open space is produced between the casings which prevents heat from hot ashes, burning cigars, etc., from being transmitted from the bottom of the inner casing to the bottom of the outer casing. There is, therefore, no possibility of tables or 30 other furniture or furnishings being injured by the heat given off of hot ashes and burning cigars deposited in the ash receiver. Another advantage of the open space between the inner and outer casings is that if the outer 35 casing should become dented at the bottom, or otherwise injured, these dents will not be apparent on the inside of the receiver.

In accordance with the provisions of the patent statutes, we have described the principle of my invention, together with the apparatus which we now consider to represent the best embodiment thereof, but we desire to have it understood that the apparatus shown is merely illustrative and that the invention 45 can be carried out in other ways.

Having now described our invention, what we claim as new and desire to secure by Letters Patent, is—

1. The combination, with an ash receiver, of a stand, and locking means inseparable from the stand for securing the two together.
2. The combination, with an ash receiver,

of a stand, the said stand having elastic legs, the said legs being separated at their upper portions to embrace the receiver, and means for simultaneously drawing all of the legs together into engagement with the receiver.

3. An ash receiver, comprising a receiver, the said receiver having a flange, and a stand having elastic legs, the said legs being separated at their upper ends to embrace the receiver, bosses on the upper ends of the legs, and means for simultaneously causing all of the bosses to engage with the flange.

4. An ash receiver, comprising a receiver, the said receiver having a flange, and a stand having elastic legs, the said legs being diverged at their upper ends to embrace the receiver, bosses on the upper ends of the legs, and means for simultaneously causing all of the bosses to engage over the flange, and to hold the receiver in engagement with the diverging portions of the legs.

5. An ash receiver, comprising a receiver with a flange thereon, a stand having elastic legs, the said legs being separated at their upper extremities, bosses on the legs, a ring surrounding the legs, and means for causing the ring to simultaneously draw all of the legs together, and engage the bosses with the flange.

6. An ash receiver, comprising a receiver and a stand, the said stand having elastic legs converging toward the top and then diverging to grasp the receiver, and a ring surrounding the converging portion, the said ring being free to move on the legs, and of less diameter than the stand, and a notch in one of the legs engaging with the ring, when the legs are in engagement with the receiver.

7. An ash receiver having an outer flat-bottomed casing, a stand removably secured thereto, in combination with an inner ash-containing casing, removably supported by the outer casing, with its bottom clear of the bottom of said outer casing, leaving a space between the bottoms of the two casings.

This specification signed and witnessed this fourth day of Feby., 1908.

JOSEF VOSKA.
CHARLES NELSON.
